No. 714,321.

J. T. MCGRATH.
PNEUMATIC HAMMER.
(Application filed Jan. 11, 1902.)

(No Model.)

Patented Nov. 25, 1902.

UNITED STATES PATENT OFFICE.

JOHN THOMAS MCGRATH, OF FORT GRATIOT, MICHIGAN.

PNEUMATIC HAMMER.

SPECIFICATION forming part of Letters Patent No. 714,321, dated November 25, 1902.

Application filed January 11, 1902. Serial No. 89,346. (No model.)

To all whom it may concern:

Be it known that I, JOHN THOMAS MCGRATH, master mechanic, of the town of Fort Gratiot, in the county of St. Clair, in the State of Michigan, have invented certain new and useful Improvements in Pneumatic Hammers, of which the following is a specification.

My invention relates to improvements in pneumatic hammers; and the object of the present invention is to devise a pneumatic hammer which will have a maximum efficiency or power for a minimum use of air and which will also have a maximum rapidity of action, and thereby be not only most economical, but have a maximum power for a given size of hammer; and it consists, essentially, of a stock or casing in which the tool is placed, a piston provided with a tapered upper end and inlet-valves the stems of which are designed to extend into the cylinder, so that the hammer in its upward stroke contacts with same and opens the valve for the admission of air to produce a rapid stroke of the hammer, the inlet-valves and passage-ways and parts being arranged and constructed in detail as hereinafter more particularly explained.

Figure 1 is a sectional view of my improved hammer. Fig. 2 is an enlarged detail of the piston. Fig. 3 is an enlarged detail of the valves, showing portion of the cylinder broken away to exhibit the passage-ways around the valves and leading into the cylinder.

In the drawings like characters of reference indicate corresponding parts in each figure.

A is the stock or casing of the hammer, which is formed integral from end to end and hollow, as shown.

A' is the usual handle, which is formed at the upper end of the casing or stock.

A² is the tool-holder in which the tool A' is held.

a is the passage-way into which the end of the tube extends by which the air is supplied to the chamber. The air passage-way extends inwardly into the annular recesses b in the screw-plug B at the upper end of the hammer.

c is the passage-way leading from the valve-chamber C into the annular recess b.

c' is a passage-way leading from the end of the valve-chamber into the annular groove b'.

C' is the plug closing the end of the valve-

chamber, and C² is a valve provided with the usual stem c² and operating-trigger c³. The annular recess b' communicates with the passage-way b², which communicates with the longitudinal passage-way a' in the casing.

a² is a passage-way leading from the opposite end of the passage-way a into the interior of the casing opposite the piston D. (See dotted lines, Fig. 1.)

The piston D is provided with a recess d and a hole d', extending outwardly therefrom, and an annular enlargement d² at the top, which is tapered at the extreme end at d³, as shown. The interior of the casing is provided with an inwardly-extending annular enlargement or shoulder a⁴, through which the piston extends.

a⁴ is an annular groove in the cylinder near the enlargement or shoulder a⁴.

a⁶ represents exhaust-holes in the lower portion of the chamber.

2 represents disk-valves provided with stems 3, such valves being located in the chamber 4 and the stems 3 of the same extending into the cylinder at a point substantially on a line with the smallest diameter of the tapered end d³ of the piston D.

5 represents a series of holes surrounding the stem of the valve and extending from inside of the disk 2 of each valve into the interior of the piston. The upper portion of the chamber in which the piston reciprocates is provided with a shoulder a⁷, so that the diameter of the upper end is slightly increased. The stems 3 of the valves are held in guiding-sockets 6 in the screw-plug 7, the inner ends of which form the outer wall of the valve-chambers 4.

8 is a passage-way leading from the passage-way c into one valve-chamber 4, and 9 is a passage-way leading from the passage-way a into the opposite valve-chamber 4.

Having now described the principal parts involved in my invention, I shall briefly describe its operation and utility.

In the operation of the hammer the air is admitted through the passage-way a and passes around the annular recess b' through the passage-way c. When the hammer has been brought into position for work, the valve-stem is pushed inwardly by means of the trigger c³. The piston is shown in the position

ready to operate. When it is raised so as to cause the tapered end d^3 to force the valves 2 from their seat, the air passes from the passage-ways c and a through the passage-ways 8 and 9, valve-chamber 4, past the valves 2, and through the passage-ways 5 into the cylinder, thereby forcing such piston down and at the same time passes into the opening a^2 . When the piston has reached the point where the hole d' passes the annular enlargement a^3 , the air exhausts through the openings a^6 at the lower end of the cylinder, and this of course takes place when such piston reaches or is reaching the limit of its downward stroke.

15 At the same time that the air is admitted past the valves 2 the air also is being admitted by means of the passage-ways b^2 , a' , and a^2 into the space in the cylinder between the upper end d^3 of the piston and the internal enlargement of the cylinder, and therefore as soon as the pressure of the air causes the valves 2 to close the passage-ways 5, leading into the cylinder, the piston which has received its impetus and is reaching the limit of its stroke 25 will upon reaching such limit be forced backwardly again by the compressed air between the enlargement d^3 of the piston and internal enlargement a^3 of the cylinder, as the air at the upper end of the cylinder will have then 30 been exhausted through the holes d' and a^6 .

The operation is of course repeated, and I find in practice is very rapid and efficient, and, in fact, so much so that I can obtain more power and do more work with my pneumatic hammer than with other hammers the stroke of which is nearly double the length to that of mine.

What I claim as my invention is—

1. In a pneumatic hammer, the combination with a casing having a supply-passage 40 for air provided with a main controlling-valve, said casing having ports for admitting air in rear of the piston, check-valves controlling said ports and having stems projecting into the casing, a piston within the casing having 45 inclines for contacting with said stems to raise the valves from their seats to admit air and propel the piston, means for admitting air to the opposite side of the piston to return it to initial position, and means whereby the air 50 is exhausted from the chamber, substantially as described.

2. In a pneumatic hammer, in combination a casing or stock provided with passage-ways and main valve for the admission of air, said casing being provided with an annular interior enlargement forming a reduced portion or shoulder intermediate of the length of the cylinder, a piston of the same diameter as the reduced portion and provided with a head of 55 corresponding diameter to the major portion of the interior of the cylinder, said head being tapered at the upper end, disk valves located in suitable chambers in the wall of the cylinder and having a stem extending through 60 the walls into the path of the tapered end of the piston, passage-ways leading through the wall of the cylinder from inside the disks of the valves, and passage-ways leading from the main admission passage-ways into the 65 valve-chambers as and for the purpose specified.

JOHN THOMAS MCGRATH.
